(57) **CLAIM**

The ornamental design for a projector, as shown and described.

DESCRIPTION

FIG. 1 is a right perspective view of a projector showing my new design;

FIG. 2 is a left perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is a right perspective view of a projector illustrating the situation that a lens is directed to first direction, showing my new design;

FIG. 10 is a front view thereof;

FIG. 11 is a rear view thereof;

FIG. 12 is a top plan view thereof;

FIG. 13 is a bottom plan view thereof;

FIG. 14 is a right side view thereof;

FIG. 15 is a left side view thereof;

FIG. 16 is a right perspective view of a projector illustrating the situation that the lens is directed to second direction, showing my new design;

FIG. 17 is a front view thereof;

FIG. 18 is a rear view thereof;

FIG. 19 is a top plan view thereof;

FIG. 20 is a bottom plan view thereof;

FIG. 21 is a right side view thereof;

FIG. 22 is a left side view thereof;

FIG. 23 is a right perspective view of a projector illustrating the situation that the lens is directed to third direction, showing my new design;

FIG. 24 is a front view thereof;

FIG. 25 is a rear view thereof;

FIG. 26 is a top plan view thereof;

(Continued)

FIG. 27 is a bottom plan view thereof;
FIG. 28 is a right side view thereof;
FIG. 29 is a left side view thereof;
FIG. 30 is a right perspective view of a projector illustrating the situation that the lens is directed to fourth direction, showing my new design;
FIG. 31 is a front view thereof;
FIG. 32 is a rear view thereof;
FIG. 33 is a top plan view thereof;
FIG. 34 is a bottom plan view thereof;
FIG. 35 is a right side view thereof;
FIG. 36 is a left side view thereof;
FIG. 37 is a right perspective view of a projector illustrating the situation that the lens is directed to fifth direction, showing my new design;
FIG. 38 is a front view thereof;
FIG. 39 is a rear view thereof;
FIG. 40 is a top plan view thereof;
FIG. 41 is a bottom plan view thereof;
FIG. 42 is a right side view thereof;
FIG. 43 is a left side view thereof;
FIG. 44 is a right perspective view of a projector illustrating the situation that the lens is directed to sixth direction, showing my new design;
FIG. 45 is a front view thereof;
FIG. 46 is a rear view thereof;
FIG. 47 is a top plan view thereof;
FIG. 48 is a bottom plan view thereof;

FIG. 49 is a right side view thereof; and,
FIG. 50 is a left side view thereof.

1 Claim, 43 Drawing Sheets
